BOAT RUDDER POSITION INDICATOR OR SIMILAR ARTICLE

Thomas H. Foster, Newtown Square, Bruno W. Kersten, Springfield, and John W. Bartley, Huntington Valley, Pa., assignors to Teleflex Incorporated, a corporation of Pennsylvania

Filed Jan. 27, 1964, Ser. No. 78,356

Term of patent 14 years

(Cl. D71—1)

FIGURE 1 is a front elevational view of a boat rudder position indicator or similar article, showing our new design;

FIGURE 2 is a left side elevational view, the opposite side being substantially a mirror image thereof;

FIGURE 3 is a left side, top and front perspective view, to a reduced scale; and

FIGURE 4 is a fragmentary perspective view thereof looking in the direction of the arrows 4—4 in FIGURE 2 perpendicular to the scale surface to illustrate the straight line appearance of the scale when viewed at this angle.

The rear is a flat, unornamented surface.

The legible matter shown in broken lines is for illustrative purposes only.

Portions of the figures are stippled to indicate contrast in appearance and portions are diagonally lined to indicate transparency.

We claim:

The ornamental design for a boat rudder position indicator or similar article, substantially as shown and described.
